Primary Examiner — Nicole C Shiflet

Assistant Examiner — Karen M. Jones

CLAIM

The ornamental design for a baffled oil catch can for diesels, as shown and described.

DESCRIPTION

FIG. 1 is a front, top perspective view of a baffled oil catch can for diesels, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The broken lines in the figures illustrate portions of the baffled oil catch can for diesels that form no part of the claimed design.

1 Claim, 8 Drawing Sheets
